UNITED STATES PATENT OFFICE.

WILLIAM F. REMPPIS, OF READING, PENNSYLVANIA.

DESIGN FOR A BICYCLE-FRAME.

45,961.

Specification for Design.

Patented June 16, 1914.

Application filed July 28, 1913. Serial No. 781,659. Term of patent 7 years.

To all whom it may concern:

Be it known that I, WILLIAM F. REMPPIS, a citizen of the United States, residing at Reading, in the county of Berks and State of Pennsylvania, have invented a new, original, and ornamental Design for a Bicycle-Frame, of which the following is a specification, reference being had to the accompanying drawing, forming part thereof.

The figure is a side elevation of a bicycle frame showing my new design, the distinctive feature of which is the straight brace

bar hooked at one end and arranged to divide the usual frame space as illustrated.

What I claim is:

The ornamental design for a bicycle frame as shown and described.

In testimony whereof I affix my signature in presence of two witnesses.

WILLIAM F. REMPPIS.
